UNITED STATES PATENT OFFICE.

NETTIE M. HOMER, OF BROOKLYN, NEW YORK.

STEAMING DEVICE.

Application filed March 8, 1927. Serial No. 173,733.

The present invention relates to improvements in steaming devices and has for its principal object to provide a simple and efficient structure wherein steam may be quickly 5 and easily generated for use in the cleaning and refreshing of velvet, or other pieces of fabric.

One of the important objects of the present invention is to provide a steaming device 10 of the above mentioned character, which includes a water reservoir which is adapted to be detachably secured on a heating unit, a steam spray nozzle being associated with the water reservoir and arranged for cooperation with the spray nozzle is a suitable cut off valve.

Another important object is to provide a steaming device of the above mentioned character, which is simple in construction, 20 strong and durable, and otherwise well adapted for the purpose for which it is designed.

Other objects and advantages of the invention will become apparent during the 25 course of the following detailed description, taken in connection with the accompanying drawing:

In the drawing, forming a part of this application, and in which like reference 30 characters designate like parts throughout the views:

Figure 1 is a perspective view of the steaming device embodying my invention.

Figure 2 is a vertical sectional view, taken 35 approximately on the line 2—2 of Figure 1, and

Figure 3 is a longitudinal sectional view, through the spray nozzle, taken substantially on the line 3—3 of Figure 1.

In the drawing, wherein for the purpose 40 of illustration is shown the preferred embodiment of my invention, the numeral 1 designates generally my improved steaming device, the same comprising a hollow base 2, 45 which is preferably in the shape of the base of an electric iron. Suitable supporting feet or legs 3 are arranged on the bottom of this base for spacing the same from the table or other support. Arranged within the hollow 50 base 2 is a heating unit 4, which includes a flat body portion, and a resistance element carried thereby. As this particular heating unit structure forms no important part of the present invention, a detailed disclosure 55 or description of the same is thought unnecessary. The current is supplied to the re-

sistance element by a suitable cable 5, which has attached at one end the plug 6 and this plug is detachably mounted in a socket 7, carried by the rear end of the iron shaped 60 base 2, and it is of course understood that the terminals (not shown) which extend into the socket are connected to the resistance 8, in any suitable manner.

A heat radiating or hot plate 9 is secured 65 on the open upper face of the hollow base and the purpose of this heat radiating plate 9 will be presently apparent.

The steaming device further includes the provision of a closed water reservoir, which 70 is of substantially the same configuration or shape as the hollow base 2 and the bottom of this reservoir is adapted to rest on the upper face of the radiating or hot plate 9. This water reservoir is detachably secured 75 on the heat radiating plate and the securing means comprises the provision of a series of spring clips 11, each of which spring clips is formed of an elongated strip of spring metal, having one end secured to the side of 80 the reservoir. The strip is bent back upon itself as at 12 and the free end portion 13 has its intermediate portion bent to form a nose 14, in the manner as clearly illustrated in Figure 2. The free end 13 is disposed 85 outwardly in diverging relation with respect to the stationary end of the strip, and furthermore, the free end portion provides a handle for facilitating the actuation of the spring clip or clasp in the manner to be pres- 90 ently apparent.

A plurality of U-shaped brackets 15 are secured to the side edges of the radiating plate 9 and the crown or base portion of each of these brackets is formed with a slot 16, 95 into which extends the nose portion 14 of each of the spring clasps in the manner as clearly shown in the drawing. In this manner the spring clasps cooperate with the brackets in detachably securing the water 100 reservoir on the heat radiating plate and whenever it is necessary to remove the water reservoir, the same can be readily and easily removed by simply pressing inwardly on the free end portions 13 to disengage the nose 105 14 from the notch or recess 16 and thus lift the water reservoir upwardly from the plate 9 through the medium of the handle 17 which is mounted on the top of the water reservoir.

The water reservoir is filled through a suitable opening 18 provided in the top of the

2
reservoir adjacent the rear end thereof and extending upwardly from this opening is the threaded neck 19 normally closed by the cap 20. This cap is formed with a central opening, in which is freely slidably the rod 21, on the lower end of which is mounted a float 22. A ball shaped head 23 is carried on the upper end of this rod and this structure provides a water gauge whereby the amount 10 of water contained within the reservoir may be readily ascertained at all times.

A steam spray nozzle 24 is formed at its rear end with a downwardly projecting neck 25 which communicates with a suitable opening 15 provided in the top of the forward portion of the reservoir. This nozzle is substantially rectangular in cross section and the steam passage tapers gradually toward the discharge end of the nozzle, whereby a 20 relatively fine spray will be emitted from the nozzle.

For the purpose of normally cutting off the discharge of the steam through the spray nozzle, I provide the vertically sliding cut-off 25 valve 26. This cut-off valve is operable within the rear portion of the nozzle and a guide 27 for the cut off valve extends upwardly from the upper face of the nozzle in the manner as clearly shown in both Figures 1 and 3. 30 An actuating knob 28 is carried by the upper edge of the cut-off valve 26 to facilitate the raising of the same.

The plate 26 forming the cut-off valve is provided with a relatively small opening 29, 35 which forms a steam escape when the cut off valve is in its lowered and closed position.

When the current is turned on, the heat radiating plate 9 will become heated by the 40 heating unit 4 and the heat will be transmitted to the reservoir 10, whereby steam will be generated within the reservoir and after the proper generation of the steam the cut off valve 26 is raised to an open position and 45 the steam is emitted off through the nozzle 24, against the velvet fabric or garment which is to be steamed. The handle 17 provides a means whereby the device may be readily and easily handled and when not in 50 use the reservoir 10 may be detached from the base and the heating plate carried thereby in the manner heretofore fully explained.

It will thus be seen from the foregoing 55 description that I have provided a novel yet simple steaming device which will, at all times, be positive and efficient in carrying out the purposes for which it is designed and the simplicity enables the same to be readily assembled or disassembled, and may fur-

thermore be manufactured at a very low cost. 60

While I have shown the preferred embodiment of my invention it is to be understood that various changes in the size, shape and arrangement of parts may be resorted to without departing from the spirit of the 65 invention or the scope of the appended claims.

What I claim is:

1. In a steaming device of the class described, a base, a heating unit carried thereby, a water reservoir supported on the base above the heating unit, a steam spray nozzle extending from the top of the water reservoir, a sliding cut off valve arranged in the spray nozzle and slidable through an opening formed therefor in one side of the spray nozzle, a guide for the slidable valve around said opening, and a handle carried by the outer edge portion of the valve for manually actuating the same. 80

2. A steaming device of the class described comprising a base, a heating unit arranged thereon, a water reservoir resting upon the heating unit on the base, a steam spray nozzle associated with the water reservoir, 85 means for detachably securing the water reservoir on the base, said means comprising a plurality of U-shaped brackets extending outwardly from the sides of the base, the crown portion of each U-shaped bracket being formed with a slot, and a plurality of spring clasps carried by the sides of the reservoir and cooperating with the slots of the respective brackets. 90

3. A steaming device of the class described comprising a base, a heating unit arranged thereon, a water reservoir resting upon the heating unit on the base, a steam spray nozzle associated with the water reservoir, means for detachably securing the 100 water reservoir on the base, said means comprising a plurality of U-shaped brackets extending outwardly from the sides of the base, the crown portion of each U-shaped bracket being formed with a slot, a plurality of spring clasps carried by the sides of the reservoir and cooperating with the slots of the respective brackets, each of said clasps being formed of a single strip of spring metal 105 bent intermediate its ends, one end portion being secured to the reservoir, the free end portion being bent intermediate its ends to provide a nose, for engagement with the respective slot, the free end forming a handle to disengage the nose from the slot in the 110 respective bracket. 115

In testimony whereof I affix my signature.
NETTIE M. HOMER.
